UNITED STATES PATENT OFFICE

CHARLES STEIN AND WILLIAM M. HELLER, OF ATLANTIC CITY, NEW JERSEY

DOLL

Application filed December 5, 1927. Serial No. 237,838.

The object of our invention is to provide in very simple and yet very attractive form, a doll, especially an infant doll, having readily movable members, especially head and arms, which by easy manipulation may be made to strikingly simulate the natural movements by a living infant of the corresponding member.

Our invention consists in whatever is described by or is included within the terms or scope of the appended claims.

In the drawings:

Fig. 1 is a perspective view of a doll embodying our invention;

15 Fig. 2 is a vertical section thereof;

Fig. 3 is a detail view in perspective from the back;

Fig. 4 is a perspective view of another embodiment of our invention.

20 Briefly describing the embodiment of our invention shown in the drawings it comprises an infant doll and a bed with pillow or a cushion upon which the doll appears to lie, with the upper part of the body, head and arms exposed above what appear to be covers for the remainder of the body, and such loose or flexible connection between the doll and the pillow or cushion as to permit movements, corresponding to an infant's movements, of the exposed members or parts, either by manipulation of the fingers thrust through an opening provided for that purpose in the bed or cushion, and into contact or engagement with the head and arm members, as well as by mere shaking, when grasping the bed or cushion by the hand.

25 Describing in detail what is shown in the drawings, there is the imitation of a bed or bedding and a pillow, the bed or bedding comprising a pad, 10 (which in a rough way may be considered as corresponding with a mattress) and a pad, 11, which may be considered as roughly corresponding to the bed clothes or covering, and between these two 30 pads is placed the lower portion of the body of the doll, the portion of the doll from the waist upwards being exposed above the top edge of the cover-pad, 11, the exposed portion including the doll head, 13, and the two 35 arms, 14, each of which terminates in an open

hand, each arm up to the wrist being hollow and flexible, and the head being hollow and having in the neck a hole, 15, through which a finger may be thrust, the head being secured at the neck to a garment-like member, 55 12, of flexible material, so that although the head is of rigid material, the head may nevertheless freely move, either in response to pressure from the inserted finger, or from the slight shaking of the pad-like supports 60 for the doll, and in like manner, the arms with the hands may be moved in simulation of the movement of an infant's arms and hands, by the thumb thrust in one arm and a finger thrust in the other arm, or the arms 65 and hands with the head may be given the desired motion by grasping the supporting pads by the hand and shaking the same. In rear of and extending above the doll head, 13, is a pad, 16, corresponding to a pillow, 70 and this pad, 16, may be a continuation of the lower pad, 10, a space or hole, 17, being left or provided at the back of the doll, so that the hand and fingers may grasp the doll body, and the appropriate fingers thrust in the 75 hollow head and the hollow arms from the rear. Preferably, at the back of the structure and reaching from the top of the pillow down to the bottom of the pad, 10, is a loose, flexible cover or curtain, 18, which 80 provides a good finish at the rear and conceals the back of the doll and the pads, 10 and 16, the cover or curtain, 18, being open at the bottom and sufficiently loose so that the hand may be thrust upward from the 85 bottom inside the curtain or covering, when the movements of the doll are to be produced by the fingers thrust into the several members.

Secured by sewing or otherwise to the 90 member, 12, below the hollow neck of the head, is a bag or sack, 20, of cotton or other suitable material so that it is flexible and within such sack is a voice-producing device, 21, of familiar construction comprising a 95 metal box with a hinged front which upon pressure, emits the desired sound and thus contained within and supported by the bag or sack it may readily be grasped by the hand inserted at the rear for manipulating 100

the doll parts. The sack hangs pendant or free from the top and thus constitutes a simple supporting means and one which permits the ready grasping of the sound-producing device. It is not necessary that the sack contain anything but the sound-producing device, and no other filling is shown in the drawings. It will be noted that the front pad, 11, lies over the front of the sound-producing device, and sufficiently high so that if the doll head should fall forward (as indicated in dotted lines, Fig. 2) which it might do by reason of the flexibility of the sack or bag, it will strike on the cushioning pad, 11, and not be defaced or broken. This would be apt to occur when the head is made of frangible material and the metal sound-producing device would be in position to receive the blow. Again if the toy is dropped to the floor, the head will be protected from defacement or injury, because of the pad, 11, and also the pad, 10, which together constitute considerable bulk of soft, cushioning material, and such pads extend at the front, the bottom and at the sides a sufficient distance to thus safeguard the head on all three sides, and, together with the location and weight of the sound-producing device, place the center of gravity of the toy sufficiently low so that tendency to fall with the head downward will be obviated. Of course the pillow pad, 16, also safeguards the head from injury.

It will be seen that the sack arrangement for containing the voice-producing device and the location of the latter so that it may be readily caught hold of by the hand, provides a body of sufficient stiffness for proper support of the toy. It will be seen that the doubling of the pads at the front and back of the body, which in effect is provided by the sound-producing device, which doubling is over the lower part, gives a cushion or pad effect and appearance that is of advantage structurally as a protecting means and in appearance in simulating the cushion or bedding effect.

A very convenient, inexpensive, attractive means of attaching the pad and curtain parts together is the use of small safety pins, 22, shown best in Fig. 3.

In Fig. 4 is shown a very simple embodiment of our invention. In this case, the body or support, 200, is in the form of an oblong, rectangular sheet of fairly thick material, and the pad, in simulation of bedding, is several loose plies, 100 and 110, of blanket-like fabric doubled or folded upon front and back of the body, over the bottom edge upward, as the pads, 10 are in Figs. 1 to 3, the top edges of the folds reaching to the bottom of the hole, 170, in the body to the edges of which are secured the hollow, flexible, garment-like member, 120, which conceals the hand when thrust through the body into the

hollow head attached to the top edge of the garment-member. The body 200, may be a sheet of cellular paper board used for packing, and therefore soft and light, and somewhat flexible. Behind the head there is a pillow pad, 160. If desired, a curtain 180, (shown in dotted lines, Fig. 4) may be used. In both forms of our invention the oblong rectangular contour is provided, which simulates admirably the conventional bedding or cushion, and has mechanical advantages, such as the doubling over to provide pads at front and back, and straight, soft edges on which the toy may stand in an upright position, when leaned against a vertical support.

What we claim is:

1. A toy figure that comprises a figure having a body, adapted to be grasped by the hand, and a flexibly supported hollow head mounted above said body, the head having a neck with an opening for thrusting a finger into the head, said opening being situated so that it is accessible to a finger of the hand grasping the doll to wiggle the head and pad means comprising portions that respectively extend from a point substantially below the head, and reach downward and laterally, and then upward, and provide overlying cushion layers, a pad in rear of the head, a curtain extending from the top of the last named pad downward, and safety pins attaching said pads and said curtain at the edges, the curtain being free at the bottom for thrusting the hand between it and the adjacent pad.

2. A toy comprising a member of substantially rectangular form with separated upper and lower parts that constitute cushions, a figure simulating the human head and arms, situated between the upper part and the lower part, said parts adjacent the head and arms being separated to provide an opening, a garment-like member to which the head at the neck is attached and which extends to the edges of the opening and it is secured to said parts whereby the head is attached to said parts by said garment-like member and by which the head is flexibly connected to said rectangular member for movement, a sack-like container, a sound-producing device within such container adapted to be grasped by the hand to manipulate said device, said device with said container being situated in rear of the lower cushion part and said container extending from said device upward into said garment-like member, and means suspending said container from its upper end.

3. A toy comprising a member of substantially rectangular form with separated upper and lower parts that constitute cushions, a figure simulating the human head and arms, situated between the upper part and the lower part, said parts adjacent the head and

arms being separated to provide an opening, a garment-like member to which the head at the neck is attached and which extends to the edges of the opening and it is secured to said parts whereby the head is attached to said parts by said garment-like member and by which the head is flexibly connected to said rectangular member for movement, a sack-like container, a sound producing device within such container adapted to be grasped by the hand to manipulate said device, said container with said device being situated in rear of the lower cushion part and said container extending from said device upward into said garment-like member, and means suspending said container from its upper end, and a curtain reaching from the upper cushion part downward at the rear and over the lower cushion part and spaced from the latter whereby an opening is provided for thrusting the hand at the rear.

In testimony whereof we hereunto affix our signatures.

CHARLES STEIN.
